Patented Feb. 17, 1920.

UNITED STATES PATENT OFFICE.

CHRISTIAN J. STARKS, OF CLOUTIERVILLE, LOUISIANA, ASSIGNOR OF ONE-HALF TO
WILLIAM A. BROWNLEE, OF COLFAX, LOUISIANA.

RAILWAY-JOINT.

1,331,396.

Specification of Letters Patent. Patented Feb. 17, 1920.

Application filed February 10, 1919. Serial No. 276,094.

To all whom it may concern:

Be it known that I, CHRISTIAN J. STARKS, a citizen of the United States, residing at Cloutierville, in the parish of Natchitoches 5 and State of Louisiana, have invented certain new and useful Improvements in Railway-Joints; and I do declare the following to be a full, clear, and exact description of the invention, such as will enable others skilled in the art to which it appertains to make and use the same.

This invention relates to railway joints, and it relates more particularly to an improved railway joint in which the joined rail 15 ends are of counterpart construction.

One of the objects of the invention, therefore, is to provide improved rails of counterpart construction, so that the rail ends are interchangeable with relation to other rail 20 ends of similar construction, and to obtain the maximum strength and rigidity consistent with the greatest simplicity of construction.

Another object is to provide a rail joint 25 of improved construction in which the rail ends are interlocked so that they are not likely to become disjoined in case one or more of the joint-bolts become broken or disengaged.

Another object is to provide a rail joint in 30 which the web portions are recessed to receive the bolt heads, thereby minimizing the probability of the bolts being sheared by the wheels of a derailed car or engine.

Other objects and advantages may become 35 apparent to persons who read the following details of description in connection with the accompanying drawings in which:—

Figure 1 is a side elevation of my im- 40 proved rail joint.

Fig. 2 is a top plan view.

Fig. 3 is a horizontal sectional view 45 through the bolt-holes.

Fig. 4 is a vertical sectional view along the line 4—4 of Fig. 2.

Fig. 5 is a vertical sectional view along 50 the line 5—5 of Fig. 2.

Fig. 6 is a vertical sectional view along the line 6—6 of Fig. 2.

Fig. 7 is a top plan view showing the rail 55 ends partly broken away and being separated from one another.

Fig. 8 is a perspective view of one of the rail ends.

Referring to these drawings in detail in

which similar reference characters correspond with similar parts throughout the several views, my improved railway joint consists of two rail ends 7, of counterpart construction, three bolts 8 and three nuts 9, 60 washers 10 being employed when desirable. These rail ends being of counterpart construction, a description of one will suffice for both.

Each rail end 7 comprises a thickened web 65 portion 11 which is substantially as thick as the horizontal extent or width of the rail head 12. Extending from the thickened web portion 11 to the extreme end of the rail is a web extension 13, the same being formed 70 with a vertical inner surface 14 which coincides with the longitudinal center of the rail.

Each rail end is formed with vertical surfaces 19 which extend diagonally through the head and base and across the middle part 75 of the web extension 13 and terminate at the extreme end 17. This construction provides a recess 20 between the rail head and rail base, this recess being of a size and shape to receive the outer end portion of the 80 web extension of the companion rail. The outer end portion of the web extension 13 is formed with downwardly inclined upper and lower surfaces 21 and 22 respectively which terminate at the vertical 85 surface 14. The lower surface of the recess 20 is upwardly and downwardly inclined at 23 in proportion to the inclination of the surface 22, so that the rail ends interlock with one another when they are fitted together as shown in Figs. 1 to 5 in the drawings.

From the foregoing it will be seen that the rail ends would not become disjoined even if they were not bolted together, but for 95 the sake of perfect security the bolts 8 and nuts 9 are secured through the apertures 24 which are sufficiently large to allow for longitudinal expansion and contraction of the rails. In order to properly seat the bolts 100 8, washers 10 and nuts 9, in view of the diagonal surfaces 19, I provide recesses 25 each of which has a vertical surface 26 extending parallel with the vertical surfaces 19, and the holes 24 are preferably at right 105 angles to the surfaces 26 so that the bolt head and washer may fit snugly on these surfaces or fastener seats 26, the bolts 8 extending diagonally through the web extensions or at right angles to said fastener seats. 110

In the operation of interlocking two rail ends of this construction, they are first placed in alinement and have the outer ends of their vertical surfaces 14 in contact 5 with one another; and they are then moved longitudinally toward one another so that the surface 22 of each rail end slides on the surface 23 of the other rail end, until the the extreme end 17 of each 10 rail end arrives at the thickened position 11 of the other rail end. When thus interlocked, the rail ends cannot be disjoined by a lateral movement horizontally. These rail ends may also be interlocked by elevating 15 their ends to be joined, inserting one of the bolts 9 through the middle holes 24 and tightening the nut of this bolt while lowering the rail ends to the horizontal position and at the same time twisting or tilting the 20 rails so that the lower edge 22 of the web extensions will be directed into the respective recesses 20, this action being permitted by the inclined and curved upper surfaces 21 and the relatively large holes 24 through 25 which the relatively small bolt extends.

Although I have described this embodiment of my invention very specifically, it is not intended to limit this invention to these exact details of construction and arrangement of parts, but I am entitled to make changes within the scope of the inventive idea disclosed in the foregoing description and following claims.

I claim:

35 1. A rail joint comprising the joined ends of two railway rails, each of said ends being formed with a web portion substantially as thick as the horizontal width of the rail's head, and a web extension substantially half 40 as thick as the horizontal width of the rail's

head, each web extension having an inner vertical surface extending substantially in a plane coinciding with the longitudinal center of the rail, the head and base flange of each rail end being formed respectively with 45 a vertical surface extending diagonally across said inner vertical surface, each of said web extensions having recesses formed in its outer vertical surface, each of said recesses having a vertical surface parallel 50 with said diagonally extending surfaces, each of said web extensions having apertures extending therethrough and communicating with said recesses, and bolts extending diagonally through said apertures of 55 said joined ends at right angles to said diagonally extending surfaces.

2. A rail joint comprising the joined ends of two railway rails, each of said ends being formed with a web portion substantially as 60 thick as the horizontal width of the rail's head, and a web extension substantially half as thick as the horizontal width of the rail's head, each web extension having an inner vertical surface extending substantially in a 65 plane coinciding with the longitudinal center of the rail, the head and base flange of each rail end being formed respectively with vertical surfaces extending diagonally across said inner vertical surface, the outer end of 70 each web extension having upper and lower surfaces downwardly inclined toward said inner vertical surface, each rail end being formed with a recess of a shape to receive and conform to the said vertical and upper 75 and lower surfaces of the web extension of the companion rail end.

In testimony whereof I have hereunto set my hand.

CHRISTIAN J. STARKS.
